RECTIFICATION SYSTEM

Willard H. Bennett, Newark, Ohio, assignor to
Slayter Electronic Corporation, a corporation
of Ohio

Application May 22, 1940, Serial No. 336,678

4 Claims. (Cl. 175—363)

My invention relates broadly to an improved rectification system for alternating current and more particularly to a method and apparatus for producing rectified current from high voltage alternating current.

This application is a continuation-in-part of my application Serial No. 224,217, filed August 10, 1938, for Rectification system.

One of the objects of my invention is to provide a method for rectifying high voltage alternating current for producing rectified current by employing the inequality of magnitude of positive and negative currents in electric discharges in a two electrode device at substantially atmospheric pressures.

Another object of my invention is to provide a system of rectification employing an arrangement of discharge points in spacial relation to a target electrode arranged in series with an alternating current supply circuit for delivering rectified current to a load.

Still another object of my invention is to provide a system of rectification in which an arrangement of discharge points in spacial relation to a target at atmospheric pressures is electrically biased from the applied energy to secure rectification of applied energy.

A further object of my invention is to provide a rectification system of the class described which is readily adaptable to multiple unit arrangement and cascade operation.

A still further object of my invention is to provide an arrangement of two electrode rectifier which is particularly effective for operation in attaching gases in which a ballasted discharge is employed between discharge points and a target, the discharge path being interposed between an alternating current source and the load.

Another object of my invention is to provide a two electrode discharge device comprising discharge points correlated for operation with respect to a target in free electron gases, the discharge device being disposed in a path intermediate an alternating current supply source and a load.

Other and further objects of my invention reside in a circuit arrangement and method of operation of a two electrode rectifier as set forth more fully in the specification hereinafter following by reference to the accompanying drawing, in which:

Figure 1 shows a two electrode rectification system embodying my invention; Fig. 2 shows a modified form of two electrode rectification system arranged in accordance with the principles

of my invention; Fig. 3 shows characteristic curves representing the magnitude of the current which passes in a discharge device operating in accordance with my invention and drawn as a function of the applied voltage between the emitter and the target electrode; Fig. 4 shows characteristic curves of the current passing in the circuit of Figs. 1 and 2 as a function of the potential difference across the secondary of the power supply transformer; Fig. 5 shows a modified circuit for a rectification system embodying my invention in which double voltage is obtained in the output of the rectifier as compared with the circuits of Figs. 1 and 2; and Fig. 6 illustrates a circuit arrangement for the cascade operation of a multiple number of rectifier circuits.

My invention is directed to an improved high voltage rectification system which makes use of a two electrode device comprising discharge points or edges directed toward a target. The discharge points or edges are connected in circuit with the alternating current supply system. The load circuit which receives the direct current is connected in a path through the discharge points and the source of applied potential. With alternating current supplied to the input system of the device, direct current is derived from the output circuit of the device. The two electrode rectifier thus formed is operative in the open air using a ballasted discharge or in an atmosphere of attaching gases or in free electron gases. The rectification system is self-biasing from the applied input potential and continuous operation of the rectifier may be maintained upon application of the applied alternating current source for deriving a steady direct current.

Referring to the drawing in more detail, Fig. 1 illustrates one rectification circuit arrangement embodying the principles of my invention and utilizing self-biasing discharge components in the two electrode device as will be hereinafter more fully understood. Reference character 1 designates the input circuit to the high voltage rectifier constituted by a primary winding of transformer 2. The secondary winding of transformer 2 is indicated at 3 having one end 4 connected to the condenser 13 and the other end 5 connected to the emitting points or discharge electrode 6. The discharge electrode 6 comprises a multiplicity of discharge points directed toward a target electrode 7. In Fig. 2 I have shown an arrangement similar to that illus-

trated in Fig. 1 except that the emitting points 6 are reversed in position with respect to the target electrode 7. The target electrode 7 connects to one end of the secondary winding 3, while the discharge points 6 connect to the load circuit. The direct current output terminals connect across the condenser 13 in both circuits as shown.

In the operation of the circuit of Figs. 1 or 2 when the voltage across the transformer secondary is gradually increased, more current will pass during those half cycles than when the points are negative than when positive, and so the condenser becomes charged at the polarity shown. Continued application of transformer voltage produces a condition where as much current passes one way as in the opposite way on successive half cycles except for the D. C. drawn to the output. This condition obtained when the condenser has an average voltage equal approximately to e_0 shown in the curve of Fig. 4. This voltage is the average of the voltages at point A and B on the positive and negative branches of the characteristic curves which are the voltage across the discharge component needed to draw the equal and opposite instantaneous current i at peak voltages. The voltages A and B are those for which the integrated currents are the same, but this differs by a factor of very low order if the condenser 13 used has sufficient capacity to keep the ripple to a small percentage of the D. C. voltage on the condenser 13.

In Fig. 3 is represented the magnitude of the current which passes in such a discharge device as a function of the voltage. It is to be observed that the current which passes when the points are negative has a greater magnitude than that of the current which passes at the same voltage when the points are positive. Likewise, the voltage required to draw any given negative current is smaller in magnitude than the voltage needed to draw a positive current of the same magnitude.

The D. C. voltage produced by the circuit of Figs. 1 or 2 can be developed with more continuous use of the transformer using the circuit shown in Fig. 5. In the circuit of Fig. 5 I provide a dual arrangement of rectification systems in which emitting points 6 coat with targets 7 disposed in series with condenser 8. A reverse arrangement of coacting electrodes is provided by an assembly of discharge points 6' coacting with targets 7' in circuit with condenser 8'. The output circuit is connected adjacent target 7 and discharge points 6' and is designated at 9. The direction of the potential difference accumulated on the two condensers 8 and 8' is made opposite by reversing the direction of the two discharge components, so that the potential difference between A and B (Fig. 4) accumulates through twice the potential on either condenser 8 or 8'. The current capacity of the circuit is the same as that of the previous circuit but the voltage is doubled in the output circuit 9 as indicated at $2e_0$.

In very high voltage rectifiers still further cascading of the elements can be used for further increasing the voltage. In Fig. 6 is shown the circuit to be used for this purpose, the dotted lines indicating that any number of successive stages can be used. In this arrangement, I have represented the input transformer generally at 2 having primary winding 1 and secondary winding 3, the terminal 14 of which connects through a series of successive condenser stages shown at 15, 16, 17, 18 and 19, etc. The opposite side 20

of secondary winding 3 connects through the discharge components illustrated at 21, 22, 23, 24, 25, 26 and 27, etc., in series. It will be observed that the discharge points of the discharge component 21 connect to one side of the line while the coacting target of discharge component 21 connects with the discharge points of succeeding discharge component 22, etc., and so on through the series of discharge components. Each pair of the discharge components is bridged by a condenser which I have illustrated at 28, 29, 30, etc. The high voltage direct current is delivered at terminals 31, 32. The dotted lines indicate that any number of successive stages may be employed. The high voltage rectifier as described herein may be used for biasing the control grid of a simple three-electrode rectifier of large dimensions. The total voltage obtained from the circuit of Fig. 6 is the voltage bias of one of the discharge components multiplied by the number of those components used in series. The circuit of Fig. 6 employs both half cycles of the transformer voltage.

I have shown the discharge system of my invention functioning generally in the open air and at substantially atmospheric pressures. Surging or arcing are prevented in the discharge system by the ballasting of the discharge members either by the construction of such members or by the inter-position of suitable resistance in circuit with the discharge members. I may also employ the ballasted discharge members in attaching gases or in free electron gases. The condenser employed in circuit with the discharge system serves to build up the bias potential to a value at which the selected bias potential on the discharge points and on the target may be maintained throughout the period of operation of the rectifier. The condenser also serves to steady the potential on the electrodes irrespective of variations in supply potential and to smooth out the rectified current supplied to the load.

While I have shown certain preferred embodiments of my invention, I realize that modifications may be made and I desire that it be understood that no limitations upon my invention are intended other than may be imposed by the scope of the appended claims.

What I claim as new and desire to secure by Letters Patent of the United States is as follows:

1. A high voltage rectifier operating below surging and arcing conditions, said rectifier comprising in combination with a source of alternating current, a set of coacting electrodes including a target electrode and a multiplicity of emitting electrodes directed toward said target electrode and maintained at substantially atmospheric pressure, a connection between the multiplicity of emitting electrodes and one side of said source, a connection between the opposite side of said source and one side of a load, a connection between said target electrode and the opposite side of the load, and a condenser connected between the last mentioned side of said source and said target electrode.

2. A high voltage rectifier operating below surging and arcing conditions, said rectifier comprising in combination with a source of alternating current, a set of coacting electrodes including a target electrode and a multiplicity of emitting electrodes directed toward said target electrode and maintained at substantially atmospheric pressure, a connection between said target electrode and one side of said alternating current source, a connection between the oppo-

site side of the alternating current source and one side of a load, a connection between said multiplicity of emitting electrodes and the opposite side of said load, and a condenser connected between the last mentioned side of said alternating current source and said emitting electrodes.

3. A high voltage rectifier comprising in combination with a source of alternating current, pairs of coacting electrodes, each pair of coacting electrodes including a multiplicity of emitting members and a target electrode, a connection between one side of said alternating current source and the multiplicity of emitting members of one of the pair of coacting electrodes, a connection between the same side of the source and the target electrode of the other pair of coacting electrodes, a connection through a condenser from the opposite side of the alternating current source and the target electrode of the first mentioned pair of coacting electrodes, a connection between the last mentioned side of said alternating current source through a con-

denser to the multiplicity of emitting members of the other pair of coacting electrodes, and an output circuit intermediate each of the condensers and the target and multiplicity of emitting members connected thereto.

4. A high voltage rectifier comprising in combination with a source of alternating current, a pair of discharge units, each including a target member and a target electrode and a plurality of emitting members directed toward the said target electrode, a connection from one side of said source to the plurality of emitting members of one of said units and the target electrode of the other of said units, capacitive connections between the opposite side of said source and the target electrode of said first mentioned unit and the multiplicity of emitting members of said second mentioned unit, and an output circuit connected to said last mentioned target electrode and said last mentioned multiplicity of emitting members.

WILLARD H. BENNETT.
